UNITED STATES PATENT OFFICE.

JAMES H. ROGERS AND CHRISTIAN G. SCHNEIDER, OF WASHINGTON, D. C.,
ASSIGNORS TO HAYWARD M. HUTCHINSON, OF SAME PLACE.

TELEPHONE.

SPECIFICATION forming part of Letters Patent No. 251,466, dated December 27, 1881.

Application filed June 14, 1881. (No model.)

To all whom it may concern:

Be it known that we, JAMES HARRIS ROGERS and CHRISTIAN G. SCHNEIDER, citizens of the United States, both residing at Washington, in the county of Washington and District of Columbia, have invented Improvements in Telephones, of which the following is a specification.

Our invention relates to telephones in which audible signals are transmitted by sound-waves in gas contained in the pipes of a building, said gas being confined and prevented from escaping by flexible diaphragms, through which the sounds are transmitted and received. The qualities necessary in a membrane for this purpose are entire imperviousness to gas, great flexibility, adapting it to respond with freedom and delicacy to the sound-waves, and sufficient strength and durability. A metallic diaphragm is not sufficiently sensitive to yield the best results, a diaphragm of rubber is too perishable, and we have not found any other manufactured material that is absolutely impervious to gas. By experiment we have found that the entrails of animals furnish the best material for the purpose. We prefer to use the intestines of hogs; but bladder is found to answer well. It will be apparent that diaphragms thus made are liable to injury by puncturing with any sharp instrument. We have therefore devised and have combined with the aforesaid flexible diaphragm a metallic shield permitting the passage of sound-waves around it, while preventing approach to the diaphragm of any hard body. As a further means of preventing any possible escape of gas, we mount the transmitting and receiving diaphragms in pipes jointed to the main gas-pipe, and furnished at the joint with a stop-cock or valve so arranged that when the transmitting or receiving instrument is drawn forward for application to the mouth or ear of the user the gas-connection will be automatically opened, and when the said instrument is removed the connection will be shut off, so that the membrane may not be exposed to the pressure of the gas when the telephone is not in use.

In the accompanying drawings, Figure 1 is a diagram, partly in section, of a telephonic apparatus illustrating our invention. Fig. 2 is a section, on a larger scale, of the transmitting or receiving instrument, or an instrument

which may be used alternately for each purpose. Fig. 3 is a horizontal section on the line 3 3, Fig. 1. Fig. 4 is a vertical section on the line 4 4, Fig. 3. Fig. 5 is a section showing a sliding instead of a turning valve.

A represents the transmitting or receiving diaphragm, formed, as already stated, of entrail or bladder or like animal membrane. This membrane is stretched within a mouth or ear piece, B, of any suitable shape, which may serve the purposes both of a transmitting and of a receiving instrument, a similar instrument being placed at each end of the telephone system, as shown at B B'.

C is the main conducting-pipe, which may constitute the ordinary gas-pipe of a building.

Our mode of transmitting telephonic signals by sound-waves through gas confined within pipes, as stated, necessitates having the gas in contact with the inner surface of the transmitting and receiving diaphragm, and we have, as already stated, found the best effects produced by using for this purpose animal membranes, which, though sufficiently strong and tenacious and impervious to perfectly confine the gas so long as they remain intact, are nevertheless liable to injury by puncturing or cutting, either by carelessness, accident, or design. We therefore fix a metallic shield, D, in front of the membrane, so as to prevent the approach of any object which might injure it. It is manifestly undesirable to have the membranes depended on to confine the gas while not in use for talking. We therefore provided our gas-telephone with a device by which the act of raising or drawing out the instrument for speaking or hearing will open communication between the gas within the pipes C and the inner surface of the transmitting or receiving membrane A, and the dropping of the instrument will close such communication. To this end we employ a movable pipe, H, to one end of which the instrument A B is connected, while the other end of said pipe is attached to a cock or valve, I, adapted to open the connection between the pipes H and C by the act of raising the pipe H or sliding it into position for use, and to close such communication by the act of restoring the said pipe.

In order to provide a call-signal which will be in constant readiness for the use of a speaker at a distant point, and will not be shut off from

communication with the interior of the gas-pipe when not in use, we employ a call-signal such as we have described and claimed in another application, consisting of a metallic diaphragm-
5 membrane, E, adapted to confine the gas within the pipes and not liable to be injured by puncturing said membrane, being in contact with the hammer F of the bell G, so as to strike the said bell by the vibration imparted by the
10 sound-waves within the pipes.

Fig. 5 shows the pipe H opened to the gas-pipe by sliding it in, and when released thrown out by a spring, h, to close it; but it is manifest that it may be arranged to open by being
15 drawn out, if preferred.

W W represent the walls of two apartments in which the respective ends or stations of the apparatus are located, the apparatus being extended to as many such apartments as desired.

20 We are aware that diaphragms of animal membrane have long been used in telephones of other kinds; but such membrane possesses peculiar value and adaptability in a gas-telephone because of its perfect impermeability
25 and its great flexibility; but, as it is inexpedient to have an animal membrane constantly exposed to the pressure of gas, the merit of this part of our invention consists in the combination, in a gas-telephone, of a diaphragm of animal membrane to confine the gas while permitting
30 the passage of sound-waves, and a valve

by which the gas-pressure may be shut off from the diaphragm when not in use.

Having thus described our invention, the following is what we claim as new therein and 35 desire to secure by Letters Patent:

1. In a gas-telephone, the combination of a transmitting or receiving diaphragm and a valve or cock by which the gas within the tubes may be shut off from said diaphragm when the 40 telephone is not in use for talking.

2. In an apparatus for conveying telephonic sounds or signals through gas or other pipes, the combination of a transmitting and receiving instrument, a movable pipe connecting said 45 instrument with the fixed or main gas-pipe, and a cock or valve at the connection between said movable and fixed pipes, adapted to be opened by moving the instrument into position for use and closed by the replacing of the same, 50 substantially as described.

3. In combination with the diaphragm A, the shield D, applied substantially as herein described, to permit the passage of sound-waves around it while protecting the said dia- 55 phragm A from injury.

J. H. ROGERS.
